United States Patent Office

Des. 203,908
Patented Feb. 22, 1966

203,908

HEATER

Walter A. Green, Texico, Ill., assignor to Lear Siegler,
Inc., Centralia, Ill., a corporation of Delaware

Filed May 17, 1965, Ser. No. 85,293

Term of patent 14 years

(Cl. D81—19)

I claim:

The ornamental design for a heater, substantially as shown and described.
